METHOD AND APPARATUS FOR STORING
GASEOUS MATERIALS IN THE LIQUID
PHASE

James O. Jackson, Crafton, Pa.

Application August 6, 1941, Serial No. 405,648

11 Claims. (Cl. 62—122)

This invention relates to a method and apparatus for the storage of normally gaseous materials in the liquid phase and more particularly to the working or live storage thereof under conditions where the amounts of such materials in storage vary from time to time by the addition and withdrawal of portions as contrasted with so-called dead storage where the materials remain in storage for a considerable length of time without addition to or withdrawal from the total volume being stored.

In the working storage of large volumes of gaseous materials such as natural gas, the practice has been to store large quantities thereof by pumping the same into containers of various kinds. Gases may be pumped into gas holders of the telescopic or rigid loaded piston type and in either case the degree of compression is very small due to the nature of the container so that to store extremely large quantities of gases, extremely large and costly containers must be provided. Gases may be compressed to a greater degree in steel or other containers such as spherical containers designed for high pressure, or they may be compressed into old exhausted gas wells in the ground. In the storage of large quantities of gas, however, the cost of the containers becomes prohibitive for if the pressure is low a great number of them are required while if the pressure is high the cost of the smaller number of containers is proportionately increased due to the increased pressure. In the case of ground storage the pressure required to place the gases back into their natural pockets and to displace the earth waters filling them is excessive, thus causing a very high pumping cost.

Gases have been stored in the liquid phase, that is, by liquefying them and transferring the liquid to suitably insulated containers, then when the gas is wanted for use it may be regasified or vaporized by the application of heat to the liquefied gas. This method of storing gas has made possible the storage of very much larger quantities of gas in a given space than any of the former methods. However, it has had the disadvantage that a large amount of mechanical power involving high operating costs has had to be provided for liquefaction and subsequent regasification purposes. This has been particularly true when all or a portion of the contents of the stored gas may be used and replaced several times each year as is customarily the case when domestic gas is stored at off-peak periods to provide for peak demand during extreme winter weather cold spells, etc. for such cold spells are usually of

only a few days' duration and between them it is usually possible to restore gas used during the peak periods.

One of the objects of my present invention is to provide a method and apparatus for the liquefaction, storage and regasification of gas under working or live storage conditions and without the necessity of performing a large amount of expensive mechanical work in so doing.

Another object of my invention resides in providing an apparatus or system by means of which gas may be stored and increased or decreased in volume or amount at will and without the expense ordinarily attached to such operations.

A further object of the invention resides in the provision of a method and apparatus by means of which liquefied gas may be regasified through heat exchange of another gaseous material which itself becomes liquefied and thus provides a reversible system, serving to make it possible both to regasify liquid gas and to increase the supply of liquid gas and all in a simple, inexpensive manner.

Other and further objects and advantages reside in the various method and apparatus combinations, subcombinations and component parts hereinafter described and claimed and in such other and further matters as will either be understood by those skilled in this art or explained in the following specification.

In the accompanying drawings in which I have illustrated a preferred form of apparatus responding to my present invention and in which like numerals designate corresponding parts:

Fig. 1 is a vertical medial section taken through my new apparatus; and

Fig. 2 is a horizontal sectional view, partly in plan, taken on the line II—II of Fig. 1 and in the direction of the arrow thereof.

Referring now to the drawings, it will be observed that 20 is a hollow spherical liquid air storage tank constructed of suitable alloy steel sheets fastened together as by welding and supported by insulating blocks 21 of corkboard or the like. Blocks 21 extend slightly more than 45° around the lower portion of tank 20 on each side of the vertical center line and are themselves supported by steel tank shell 22 concentric to tank 20 and which may be made of ordinary sheet steel fastened as by welding, riveting or the like. Outer shell 22 is supported at about its vertical mid-point by steel columns 23 which rest on concrete foundations 24 embedded in the earth. Completely filling the space between tank 20 and spaced shell 22, not occupied by 21, is

heat-insulating material 25 which may be of a granular nature such as granulated cork, this material being preferred for the non-load bearing portion of the insulation because of its lower cost. A substantially cylindrical extension 26 projects upwardly from the top of shell 22 and is also filled with granular cork or the like. Vent pipe 27, which is sealed to 26 by stuffing box 28, extends through extension 26 and the cork therein and communicates with the interior of tank 28. Pipe 27 terminates at its upper extremity in a manifold 29 which is closed at one end by the rupture disc 30 and at the other end by a pressure-vacuum control valve 31.

Inlet and outlet pipe 32 is connected into tank 20 at the lowest point of such tank and is surrounded by pipe insulation 33 which is preferably of the molded cork type well cemented and covered. Pipe 32 is valved at 40, the valve stem projecting through the covering 33' for insulation 32, as shown.

20a is a sheet metal spherical shell for the storage of liquid gas and is identical in construction with shell or tank 20. The associated parts are likewise similar to those already described in connection with tank 20 as will be denoted by the use of corresponding numerals but followed by an "a." Vent pipe 27a is, however, additionally provided with a horizontal branch pipe 34 valved at its distal end as at 35.

Located suitably between liquid air tank 20 and liquid gas tank 20a is a vertical heat exchanger or column extending approximately from the ground to the elevation of the tops of the liquid air and the liquid gas tanks and having a sheet metal inner shell 36 and a sheet metal outer shell 37, the space therebetween being filled with granulated insulating material 25c. Serving as a support for 36 and 37 is a metal base 38 which is positioned on the concrete foundation 39. Pipe 32 connects with the interior of shell 36 near its lower end and pipe 32a, which passes through shell 36, connects with the interior of tube 42 near its bottom. Tube 42 is provided with a central rod 41 which carries and acts as a support for the baffles 54 which are staggered with respect to baffles 53 extending inwardly from tube 42. Baffles 52 extend outwardly from tube 42 and are staggered relative to the baffles 51 which project inwardly from shell 36. The lower end of pipe 44 extends into the top of tube 42 and is held in position by a flange arrangement 43. A stuffing box arrangement 45 seals pipe 44 to shell 36. An extension 46 of pipe 44 is sealed at one end to stuffing box 45 and another stuffing box or flange assembly 47 seals the upper end of pipe 46 to shell 37. A suitable valve or fitting 48 is provided on the upper end of pipe 46 for a purpose to be described. A branch pipe 49, having a valve 50 at its outer end, extends through shell 37 and communicates with the interior of shell 36. Pipes 46 and 44 constitute gas inlet means and branch pipe 49 constitutes an air inlet means.

In the operation of my device the liquid gas tank 20a is first filled to its normal working level, which makes it approximately full but leaves sufficient free space to allow continuous venting of any generated gas without causing liquid to foam through vent pipe 27a. Valve 40a is normally closed and pressure and vacuum relief valve 31a is set to limit the safe operating pressure and vacuum. I prefer to use a setting of 5 pounds per square inch pressure and about 1 ounce per square inch vacuum.

Rupture disc 30a is designed to break at a pressure of the of the liquid air is 318° Fahren-

5 pressure of about 10 pounds per square inch and serves to positively vent the tank contents in case of failure of valve 31a to operate. Because of a continual infiltration of heat through insulation 21a and 25a the liquid gas is being constantly vaporized and this vapor passes off through vent pipe 27a and, normally, through pressure-vacuum relief valve 31a. When it is desired to remove some gas from storage, air is pumped through pipe 49 under enough pressure to cause it to liquefy and flow into tank 20. Valve 40a is then opened and valve 48 slightly opened. This will allow the liquid gas to flow through pipe 32a into tube 42 where it will assume some level which may be regulated by the extent of the opening of valve 48. The heat from the incoming air in shell 36 is absorbed by the liquid gas and as the latter is volatilized it rises, passing around baffles 53 and 54 and finally out through 44 and 46. The total heat exchanging surface is sufficient to transfer the heat from the incoming air to the liquid gas so that the temperature of the gas leaving valve 48 is only slightly below that of the air entering through valve 50. It is thus seen that as air is introduced through valved pipe 49, it liquefies, gradually filling the liquid air tank 20, while the liquid gas is evaporated, causing tank 20a to empty gradually.

30 When it is desired to put more gas in storage, valves 40 and 40a are opened, valve 50 partially opened and gas is introduced through valve 48 at a pressure of only a few pounds per square inch or just enough to move the required volume into the liquid gas tank 20a. The liquid air rises in shell 36, and, through the shell of tube 42 and the baffles or fins shown cools the incoming gas, causing it to become liquid and to flow into the liquid gas tank 20a. At the same time the liquid air in shell 36 is vaporized and, by proper adjustment of valve 50, can be so regulated as to leave through 46 at a pressure only slightly below that of the gas entering via valve 48. If this operation is continued the gas tank may be completely 45 filled, with the result that the liquid air tank will be substantially emptied.

50 It is thus seen that a large quantity of gas may be liquefied and placed in storage or may be regassified and taken from storage with the expenditure of only a relatively small amount of energy, that is, only enough to overcome the internal friction and to cause the required volume of gaseous air or gas to flow into and out of the system.

55 Of course, the temperatures at which the air and the gases liquefy must be compatible although they need not be identical. For example, air liquefies at a critical temperature of approximately 221° below zero Fahrenheit and at an absolute pressure of 547 pounds per square inch while natural gas or methane liquefies at a critical temperature of 117° Fahrenheit below zero at a pressure of about 673 pounds per square inch. However, the temperature of liquid methane at a pressure of one atmosphere is approximately 260° below zero Fahrenheit while the vapor pressure of liquid air at this temperature is approximately 175 pounds per square inch absolute and the temperature of liquid air is approximately 319° below zero Fahrenheit at a pressure of one atmosphere. It is, therefore, apparent that the methane will liquefy at zero pounds gauge pressure when reduced to minus 260° Fahrenheit below zero, which it will easily be because the tem-

heat below zero when the gas is being withdrawn. Since the temperature of the liquid gas is 260° below zero Fahrenheit the air must be compressed to a pressure of about 175 pounds per square inch or more in order for it to liquefy. These pressures may be regulated either manually or automatically by manipulation of valves 40 and 40a.

Since the total heat required to be removed from 1 pound of methane gas at normal temperature in order to cause it to liquefy is approximately twice that required to be removed from 1 pound of air, it follows that provision for storage of approximately twice the weight of air as compared with the desired weight of gas must be provided.

There is a continual vaporization in both the liquid air and the liquid gas because of the infiltration of heat through the insulation. This may be offset by the addition periodically of small quantities of liquid air into the liquid air container.

Gas which normally evaporates from the liquid gas container due to the infiltration of heat through the insulation may be conducted by valved branch pipe 34 to a suitable container or to the gas mains, or may be returned through valve 48 and liquefied in the usual manner.

The foregoing is intended as illustrative and not as limitative and, without departing from the scope or principles hereof, I may resort to various modifications, additions, omissions and substitutions. The invention is rather defined by the appended claims.

Having thus described my invention, what I claim as new and desire to secure by Letters Patent is:

1. Apparatus for the storage of one kind of a gaseous material in its liquid phase and for regasifying the said stored liquefied gas by means of a second kind of gaseous material which comprises an insulated container for each such material, a heat exchanger for exchanging heat between the gaseous and liquid materials in such containers and for causing the initially gaseous material to become liquefied and the initially liquid material to become gasified.

2. Apparatus for the storage of one kind of a gaseous material in its liquid phase and for regasifying the said stored liquefied gas by means of a second kind of gaseous material which comprises a heat exchanger for exchanging heat between such gaseous and liquid materials and for causing the initially gaseous material to become liquefied and the initially liquid material to become gasified, and means for reversing the liquefying and gasifying conditions to restore the original phases of the materials.

3. Apparatus for the liquefaction and regasification of a gaseous substance which comprises an insulated container for the storage of the gaseous substance in liquid phase and an insulated container for the storage of another gaseous substance also in liquid phase and a heat exchanger in operative relationship with said containers, the construction and arrangement being such as to remove the heat from the first gaseous material causing it to liquefy by the vaporization of the liquefied second gaseous material.

4. An apparatus of the character described which comprises a heat exchange unit, a pair of insulated tanks operatively associated with said heat exchange unit, means for introducing liquefied gas into one of said tanks and means for

70 withdrawing regasified gas from that same tank, said liquefaction and regasification being effected through gasification and liquefaction of air which acts through said heat exchange unit.

5. An apparatus of the character described which comprises a heat exchange unit, a pair of insulated tanks operatively associated with said heat exchange unit, means for introducing liquefied gas into one of said tanks and means for withdrawing regasified gas from that same tank, said liquefaction and regasification being effected through gasification and liquefaction of air which acts through said heat exchange unit and said heat exchange unit including an outer shell, a second shell within and spaced from said outer shell, heat insulation filling the space between such shells, a tubular member within and spaced from said second shell, means for effecting communication between said liquid gas tank and the interior of said tubular member and means for effecting communication between the other tank and the interior of said second shell.
- 10 6. An apparatus of the character described which comprises a heat exchange unit, a pair of insulated tanks operatively associated with said heat exchange unit, means for introducing liquefied gas into one of said tanks and means for withdrawing regasified gas from that same tank, said liquefaction and regasification being effected through gasification and liquefaction of air which acts through said heat exchange unit and said heat exchange unit including an outer shell, a second shell within and spaced from said outer shell, heat insulation filling the space between such shells, a tubular member within and spaced from said second shell, means for effecting communication between said liquid gas tank and the interior of said tubular member and means for effecting communication between the other tank and the interior of said second shell.
- 15 7. An apparatus of the character described which comprises a heat exchange unit, a pair of insulated tanks operatively associated with said heat exchange unit, means for introducing liquefied gas into one of said tanks and means for withdrawing regasified gas from that same tank, said liquefaction and regasification being effected through gasification and liquefaction of air which acts through said heat exchange unit and said heat exchange unit including an outer shell, a second shell within and spaced from said outer shell, heat insulation filling the space between such shells, a tubular member within and spaced from said second shell, means for effecting communication between said liquid gas tank and the interior of said tubular member and means for effecting communication between the other tank and the interior of said second shell, a system of staggered baffles being provided between the second shell and the tubular member and interiorly of the said tubular member.

- 20 8. An apparatus for storing a gaseous material in its liquid phase and for regasifying the same by means of a second gaseous material which comprises a pair of spaced containers each of which is adapted to receive and store a liquefied gas and each of which is insulated against the infiltration of heat thereinto and an insulated heat exchange tower located in the space between said containers and operatively connected thereto.
- 25 9. An apparatus for storing a gaseous material in its liquid phase and for regasifying the same by means of a second gaseous material which comprises a pair of spaced containers each of which is adapted to receive and store a liquefied gas and each of which is insulated against the infiltration of heat thereinto and an insulated heat exchange tower located in the space between said containers and operatively connected thereto.
- 30 10. An apparatus for storing a gaseous material in its liquid phase and for regasifying the same by means of a second gaseous material which comprises a pair of spaced containers each of which is adapted to receive and store a liquefied gas and each of which is insulated against the infiltration of heat thereinto and an insulated heat exchange tower located in the space between said containers and operatively connected thereto.
- 35 11. An apparatus for storing a gaseous material in its liquid phase and for regasifying the same by means of a second gaseous material which comprises a pair of spaced containers each of which is adapted to receive and store a liquefied gas and each of which is insulated against the infiltration of heat thereinto and an insulated heat exchange tower located in the space between said containers and operatively connected thereto.
- 40 12. An apparatus for storing a gaseous material in its liquid phase and for regasifying the same by means of a second gaseous material which comprises a pair of spaced containers each of which is adapted to receive and store a liquefied gas and each of which is insulated against the infiltration of heat thereinto and an insulated heat exchange tower located in the space between said containers and operatively connected thereto.
- 45 13. An apparatus for storing a gaseous material in its liquid phase and for regasifying the same by means of a second gaseous material which comprises a pair of spaced containers each of which is adapted to receive and store a liquefied gas and each of which is insulated against the infiltration of heat thereinto and an insulated heat exchange tower located in the space between said containers and operatively connected thereto.
- 50 14. An apparatus for storing a gaseous material in its liquid phase and for regasifying the same by means of a second gaseous material which comprises a pair of spaced containers each of which is adapted to receive and store a liquefied gas and each of which is insulated against the infiltration of heat thereinto and an insulated heat exchange tower located in the space between said containers and operatively connected thereto.
- 55 15. An apparatus for storing a gaseous material in its liquid phase and for regasifying the same by means of a second gaseous material which comprises a pair of spaced containers each of which is adapted to receive and store a liquefied gas and each of which is insulated against the infiltration of heat thereinto and an insulated heat exchange tower located in the space between said containers and operatively connected thereto.
- 60 16. An apparatus for storing a gaseous material in its liquid phase and for regasifying the same by means of a second gaseous material which comprises a pair of spaced containers each of which is adapted to receive and store a liquefied gas and each of which is insulated against the infiltration of heat thereinto and an insulated heat exchange tower located in the space between said containers and operatively connected thereto.
- 65 17. An apparatus for storing a gaseous material in its liquid phase and for regasifying the same by means of a second gaseous material which comprises a pair of spaced containers each of which is adapted to receive and store a liquefied gas and each of which is insulated against the infiltration of heat thereinto and an insulated heat exchange tower located in the space between said containers and operatively connected thereto.
- 70 18. An apparatus for storing a gaseous material in its liquid phase and for regasifying the same by means of a second gaseous material which comprises a pair of spaced containers each of which is adapted to receive and store a liquefied gas and each of which is insulated against the infiltration of heat thereinto and an insulated heat exchange tower located in the space between said containers and operatively connected thereto.
- 75 19. An apparatus for storing a gaseous material in its liquid phase and for regasifying the same by means of a second gaseous material which comprises a pair of spaced containers each of which is adapted to receive and store a liquefied gas and each of which is insulated against the infiltration of heat thereinto and an insulated heat exchange tower located in the space between said containers and operatively connected thereto.

is adapted to receive and store a liquefied gas and each of which is insulated against the infiltration of heat thereinto and an insulated heat exchange tower located in the space between said containers and operatively connected thereto, 5 said heat exchange tower being provided internally with a plurality of sets of staggered baffles so constructed and arranged as to secure a substantially complete exchange of heat between fluids without undue infiltration of heat into the exchanger.

10. Apparatus for storing a gaseous material in its liquid phase and for regasifying the same by means of a second gaseous material, which comprises a pair of spaced substantially spherical containers, a substantially similarly shaped metallic shell disposed around and spaced from each such container, molded cork insulating blocks disposed in the bottom portion of each such shell and arranged to support substantially the entire weight of the container located therein, granular cork filling the remaining space between each

15 container and its shell, means for introducing fluid into and removing fluid from each such container and means for venting each such container when under excess pressure conditions.

11. Apparatus for storing a gaseous material in its liquid phase and for regasifying the same by means of a second gaseous material, which comprises a pair of substantially spherical containers spaced one from another, a heat exchange tower disposed between such containers and operatively connected to each of the same; said tower including a pair of spaced inner and outer metallic shells with granular heat insulating material filling the space therebetween; the inner shell being in communication with one such container, a central tube disposed within the inner of such shells and being in communication with the other container, and a system of baffles disposed both internally and externally of said central tube.

20 JAMES O. JACKSON.
